MACHINE FOR APPLYING MORTAR BONDING MATERIAL TO BUILDING BLOCKS

George W. Walker, Columbus, Ohio, assignor to Owens-Illinois Glass Company, a corporation of Ohio

Application April 22, 1948, Serial No. 22,628

7 Claims. (Cl. 91—45)

1

My invention relates to machines for applying coating materials to building blocks or other articles by a spraying process. The invention in the form herein illustrated is particularly adapted for applying to the surfaces of building blocks made of glass or similar material, a coating providing a rough surface such as is required for making a good bond with the mortar as the blocks are built into a wall or other structure. The coating material comprises a liquid cement or paint applied by a spray gun to the surfaces to be coated, a final coating of sand, grit or the like being then applied as by means of spray guns to the layer of cementing material. The coated blocks may thereafter be baked in an oven for setting and hardening the cementing material.

An object of the invention is to provide a machine by which the building blocks or like articles are coated in the manner indicated, in rapid succession.

Other objects of the invention will appear hereinafter.

Referring to the accompanying drawings:

Fig. 1 is a part-sectional side elevation of the coating machine, parts being broken away;

Fig. 2 is a detail view showing a valve in an air line, a mask shifting device, and cams for operating said parts;

Fig. 3 is a part sectional plan view of the machine;

Fig. 4 is a cross-sectional elevation at the line 4—4 on Fig. 3, on a somewhat larger scale;

Fig. 5 is a sectional elevation at the line 5—5 on Fig. 4;

Fig. 6 is an elevational view showing the spray gun applying a coating of liquid cement to a building block;

Fig. 7 is a detail view of the spray gun as viewed in a direction at right angles to that of Fig. 6;

Fig. 8 is a fragmentary plan view of the conveyor for delivering the blocks to the spraying machine, and a time relay switch actuated by the blocks;

Fig. 9 is an elevational view showing particularly the lifting device for the blocks;

Fig. 10 is a wiring and pipe line diagram of the operating and controlling mechanism.

The machine comprises, in general terms, a series of carriers 15, each including a mask 22, which operate in pairs to grip the blocks B or workpieces which are to be coated, pairs of endless conveyor elements in the form of chains on which the carriers 15 are mounted, each said pair including an upper chain 16 and a lower chain 17, a motor 18 (Fig. 1) operating through a train

2

of gearing as hereinafter described to drive the conveyor elements continuously, a carrying-in belt conveyor 20 (Figs. 3, 8 and 9) by which the blocks are advanced to the machine, a lifting device 21 to receive the blocks from the conveyor 20 and by which the blocks are lifted into position to be gripped by the pairs of masks 22, a rack 23 (Fig. 3) and pinions 24 for rotating the carriers 15 and blocks carried thereby, a spray gun 25 (herein referred to as a paint gun) for spraying the paint or bonding material to the surfaces of the rotating blocks, applicators 26 for applying a coating of grit, sand or other surfacing material over the bonding material. A conveyor 27 carries the coated blocks away from the machine.

A more detailed description of the machine is as follows:

As shown in Fig. 1, the motor 18 is mounted on the machine frame 30 and is operatively connected to the several conveyor chains through trains of gearing including a shaft 32 driven from the motor through speed reduction gearing in a gear box 31. A sprocket chain 33 driven from the shaft 32 drives a horizontal shaft 34 (Figs. 1 and 4). The shaft 34 operates through pairs of bevelled gears, each comprising gears 35 and 36, to drive vertical shafts 37 (Figs. 1 and 3) to each of which is keyed a lower sprocket wheel 38 and an upper sprocket wheel 39 over which the lower and upper chains 17 and 16, respectively, are trained and by which said chains are continuously driven. The chains 16 and 17 are trained over idler sprockets 38' and 39' on shafts 37' at the intake end of the machine. The conveyor 20 is driven by the shaft 34 operating through a sprocket chain 40, shaft 41 and chain 40'.

The blocks B, when placed on the conveyor 20, are carried forward between stationary guide rails 42 to the lifting device 21 by which the blocks are lifted a short distance into position to be gripped between the masks 22. The lifting device (Fig. 9) comprises a lifting plate or pad 43 carried on a vertical shaft or stem 44 connected through a link 45 to a lever arm 46 fulcrumed to swing up and down about a pivot pin 47. The arm 46 is swung upwardly by a cam 48 on the shaft 41, said cam engaging a follower roll 49 on the arm 46. A coil spring 50 holds the roll 49 on the cam and serves to lower the pad 43.

Each carrier 15 comprises a horizontal shaft 51 mounted for rotation in a bearing block 52. Vertically disposed arms 53 which may be formed integral with the bearing block 52 are connected

to the chains 16 and 17 by means of angle plates or brackets 54 and bolts 55. Each shaft 51 carries or has formed thereon a square guide block 56 to which is connected a frame 57 carrying the mask 22. The latter is yieldingly mounted for horizontal movement by means of pins 58 attached to the mask and extending through openings in the four corners of the frame 57. Coil springs 59 mounted on the pins 58 are held under compression between the frame 57 and the mask and serve to hold the latter against the workpiece B with a yielding pressure.

Each shaft 51 of the carriers 15 on one side of the machine has keyed thereto one of the pinions 24. On the other side of the machine, heads 61 are attached to the shafts 51. On each carrier a coil spring 62 surrounds the shaft 51 and is held under compression between the head 61 (or pinion 24) and the bearing block 52. After a block B has been gripped between a pair of masks 22 as hereinafter described, the masks are held in gripping engagement with the block during its passage through the machine, by means of a pair of stationary rails 63 extending lengthwise of the machine, the shafts 51 being formed with rounded ends or knobs 64 which bear against the rails 63.

The carry-in belt conveyor 20 is provided with flights 65 which serve as a positive means for advancing the blocks and for moving them off the conveyor onto the pad 43 (Figs. 3 and 9). As the block moves forward onto the pad 43, it is arrested in a central position thereon by a stop 66 (Fig. 9). The stop is mounted in a fixed position by a stationary bracket 67 bolted to a housing 68 which encloses the cam 48 and associated mechanism. The block B, as it moves into position on the pad 43, slides beneath a brake shoe 70 which serves as a friction brake to slow down the block which moves rapidly off the conveyor and has considerable inertia. The brake shoe is yieldable upwardly against the downward pressure of coil springs 71 mounted on vertical rods 72 and held under compression between the brake shoe and collars 73 fixed to said rods. The rods extend upwardly through openings in a plate 74 in which they are slidable up and down. The plate 74 is positioned beneath a cross bar 75 (Fig. 4) extending across the machine and bolted to the machine frame. The cross bar 75 has a frame 76 bolted thereto and providing a support for a microswitch 77 mounted at the upper end of the frame. A vertical rod 78 mounted for up-and-down movement in the frame 76, carries at its lower end a head 79, directly over two of the rods 72. When a block B is moved upward from the full line position, Fig. 9, to the broken line position, the rods 72 engage the head 79 and move the rod 78 upwardly a short distance, thereby actuating the microswitch 77 to control the operation of the paint gun as hereinafter described. A nut 81 threaded on the rod 78 limits the downward movement of the rod.

The cam 48 is timed to lift the pad 43 from its lowered position to the dotted line position, Fig. 9, as soon as a block has been positioned thereon, as above described.

Immediately after the block B has been lifted by the pad 43, it is gripped by a pair of masks 22 which, as they are carried forward by the conveyor chains 16, 17, are moved inwardly transversely to the chains by means of rock arms 83 which are pivoted at 84 and form extensions of the rails 63. The arms 83 are in position to engage a pair of the carriers 15 when they are directly opposite the pad 43 and in line with a

block thereon. As the carriers are moving into this position, the arms 83 are swung inwardly about their pivots by cams 85 (Fig. 2) fixed to vertical shafts 86. The shafts 86 are geared by sprocket chains 86a (Fig. 3) to the shafts 37'. The cams 85 operate positively to swing the arms 83 inwardly into substantial alignment with the rails 63, thereby moving the shafts 51 inwardly against the expansive force of the coil springs 62 so that the shields or masks 22 are brought into contact with the block B and the coil springs 59 placed under compression to hold the masks with a yielding pressure against the blocks.

In order to hold the masks against rotation during the greater portion of their travel and squared with the blocks B as the masks are moving to holding position, stationary rails 87 are mounted by means of brackets 87' in position to provide a support for the square guide blocks 56. As the major or vertical sides of the block B, as well as the masks, are square, the masks can fit the blocks in any of the four rotative positions in which the guide blocks 56 can seat on the rail 87.

As a block B, gripped between a pair of masks, moves forward beyond the pad 43, the guide blocks 56 run off the rails 87, leaving the carriers 15 free for rotation about their axes. The workpieces are positively rotated during their passage through the surface treating zones including the spraying zone, and the applicator zone in which the surface coating of grit is applied, the rotation of the workpieces being effected by means of the stationary rack 23 and pinions 24.

The spray gun 25 is adapted for spraying the four narrow sides of the block B with a bonding material such as a liquid cement, paint or the like. The term paint as herein used is intended to include any such bonding material. The gun is mounted over the path of the workpieces a short distance in advance of the lifting pad 43 and applies a layer or coating of the bonding material after the rotation of the workpiece commences. The gun is supplied with the liquid spraying material through a pipe 90 leading from a drum 90a. Valve controlled air under pressure is intermittently supplied through a pipe 91 to the gun 25, as hereinafter described, for opening and closing the nozzle. A pipe 92 supplies air continuously to the gun at a suitable pressure for atomizing the paint.

The gun is carried on a horizontal rock shaft 93 journaled in stationary brackets 94 supported on the machine frame. As a rotating block B advances beneath the spray gun, the nozzle 95 directs a spray 96 (Fig. 6) onto the surfaces to be coated. The rotation of the block B is sufficiently rapid to permit all four sides to be completely covered with the coating material during the passage of the block beneath the spray gun.

In order to direct the spray centrally of the block as the latter travels therebeneath, the gun is given a rocking movement by which the nozzle is caused to advance with the block as a whole and at substantially the same speed. This rocking movement is effected by means of a rock arm 97 fixed to one end of the rock shaft 93 and extending downwardly therefrom into the path of the arms 53 as shown in Figs. 4 and 5. After an arm 53 has passed the rock arm 97, the latter is returned by means of a torsion spring 98 mounted on the shaft 93.

After a block has passed the spray gun 25, and while still rotating, it is carried beneath a series of applicators 26 by which a coating of sand, grit or the like is applied to the block and adhered

thereto by the coating of paint or liquid cement. The applicators are provided with nozzles 99 having elongated outlet openings extending transversely of the path of the blocks and through which the material is discharged continuously by gravity. The blocks are thus provided with a rough surface adapted for bonding the mortar used when the blocks are built into a wall or other structure. The spray material for the applicators 26 is supplied through pipes 101 extending from a hopper 102 of a supply tank mounted over the spraying machine.

Referring to Fig. 10 the motor 18 is connected in a three-phase system comprising mains *a*, *b*, *c*. The motor may be started by operating a push button switch 105 and stopped by operating the switch 106. A safety device is provided for automatically stopping the motor in the event that two blocks are inadvertently placed in the same flight and brought together to the spraying machine by the conveyor 20. Such safety means includes a switch 107 in the path of the blocks *B* and actuated by each block as it is advanced by the conveyor 20. The switch 107 is in circuit with an electromagnet coil 108 of a time delay device 109. As each block *B* closes the switch 107, the coil 108 is energized and drives its armature to the left with a slow or retarded movement caused by the dash pot action of the delay device. If two blocks *B*, *B'* are traveling together, as shown, the switch 107 is held closed, thereby a sufficient length of time to permit the solenoid 108 to open a switch 110 in the control circuit of the motor, thereby stopping the motor so that the operation of the machine is discontinued until the operator removes the block *B'* and again starts the motor. In normal operation with a single block *B* at a time passing over the switch 107, the latter is released and again opened before the time delay device can operate to stop the motor. The time delay device 109 may represent any approved timer. I have found in practice, an electronic time delay device gives satisfactory operation.

The paint gun 25 is operated periodically under the control of an operating valve 112 (Figs. 2 and 10). The valve includes a plunger 113 actuated by a cam 114 on the shaft 86, said cam operating through a pivoted arm 115 to actuate the plunger and open the pressure line 91 leading to the paint gun. When air pressure is thus supplied to the gun, plunger 116 is lifted, thereby lifting the needle valve 117 and opening the pipe line 90. The spray 96 (Fig. 6) of paint supplied through the pipe 90 and atomized by the pressure air supply through the pipe 92, operates as before described, to coat the rotating block which is passing beneath the gun.

In order to prevent such operation of the spray gun in the event that a block *B* is missing, that is, when there is no block beneath the spray gun, the following safety mechanism is provided: a solenoid valve 118 actuated by a solenoid 119, is provided in the air pressure line leading to the operating valve 112. A relay switch 120 is connected in circuit with the coil 119 and is actuated by a solenoid 121 in circuit with the switch 71. When the rod 78 (Figs. 4 and 10) is moved upward as hereinbefore described, that is, when a block *B* is lifted into position to be gripped by a pair of masks 22, said rod closes the switch 71 so that the relay switch 120 is closed by its coil 121. This in turn causes the operation of the solenoid valve 118, moving the valve plunger to the left and thereby connecting an air pressure

line 122 through said valve to a pipe 123 leading to the operating valve 112, so that when the latter is operated by its cam, pressure air is supplied to the paint gun. In the absence of a block *B*, that is, if the lifting pad 43 is empty when lifted, the switch 71 remains open and the air pressure line remains closed at the valve 118, so that the cam actuated operating valve 112 is ineffective for establishing a pressure line to the paint gun and the latter remains inoperative. The relay coil 121 may operate through a time delay device 124 which delays the closing of the switch a short time, sufficient to permit the block *B* which is to be sprayed, to be brought under the spray gun.

Modifications may be resorted to within the spirit and scope of my invention.

I claim:

1. Apparatus for applying a surface coating to rectangular blocks, said apparatus including a horizontally traveling conveyor, means for driving the conveyor, carriers connected to the conveyor at intervals therealong, and traveling therewith, each said carrier including a rotatable shaft extending transversely of its direction of travel with the conveyor and mounted for rotation about its axis, a rectangular mask connected to the shaft to rotate therewith and having a block engaging surface rotatable with the shaft and in a plane perpendicular to the axis of the shaft, automatic means for positioning a said block to be engaged by said mask, automatic means operable during the travel of the mask with the conveyor for squaring the mask with the block, and means for automatically engaging the mask with the said block during the travel of the mask after it is squared with the block.

2. Apparatus for applying a surface coating to rectangular blocks, said apparatus including a horizontally traveling conveyor, means for driving the conveyor, carriers connected to the conveyor at intervals therealong and traveling therewith, each said carrier including a rotatable shaft extending transversely of its direction of travel with the conveyor and mounted for rotation about its axis, a rectangular mask connected to the shaft to rotate therewith, automatic means for positioning a said block to be engaged by said mask, means for causing the mask to engage the block, a stationary guide rail, a rectangular member connected to the shaft and running on said guide rail for holding the mask and block in a predetermined rotative position, a spray gun positioned adjacent to the path of said block and in advance of said guide rail, and means for rotating the mask and said block while passing the spray gun.

3. In a machine for coating blocks, the combination of a conveyor comprising horizontally spaced horizontally traveling endless conveyor elements, means for driving the conveyor, carriers arranged in pairs and connected to and spaced at regular intervals along the conveyor, the carriers of each pair being connected respectively to the two conveyor elements, each carrier comprising a mask having a flat surface parallel to the path of said carriers, and having a circumferential lip surrounding said flat surface and projecting outwardly away from said carrier, automatic means for actuating the carriers and moving the masks into position to grip a block placed in position between the carriers and thereby causing the block to be advanced with the carriers.

4. The combination of a conveyor comprising

horizontally traveling conveyor elements, driving means therefor, workpiece carriers connected to travel with the conveyor in a horizontal path, positioning means for moving workpieces in succession into position to be gripped by a pair of said carriers, a spray gun having a stationary mounting over the path of the workpieces and in advance of said positioning means and arranged to direct a spray onto a workpiece when the latter is carried therebeneath, means providing an air pressure line extending to the spray gun, said gun comprising a valve opened by air pressure through said line, an operating valve in said air pressure line, and automatic means for periodically actuating said operating valve in timed relation to the movement of the workpieces by said positioning means.

5. The combination set forth in claim 4 wherein in a solenoid valve is connected in said air line in series with said operating valve, and electroresponsive means actuated by the operation of the positioning means for moving a said workpiece, to effect the operation of the solenoid valve and thereby open the air pressure line leading to the operating valve.

6. A machine for applying a surface coating to building blocks comprising gripping devices for gripping the blocks, means for advancing the gripping devices and blocks in a predetermined path, a spray gun having a stationary mounting in position to direct a spray against the blocks during their travel, means for advancing the blocks singly and in succession for delivery to the gripping devices, means for causing the blocks to be gripped by said gripping devices, a motor, driving connections between the motor and the said means for advancing the gripping devices, and automatic means for stopping the motor when more than a single block at a time is advanced for delivery to the gripping devices.

10
15

20
25

30
35
40

7. A machine for coating blocks, comprising a conveyor including horizontally spaced horizontally traveling endless conveyor elements, means for driving the conveyor, carriers arranged in pairs and connected to and spaced at regular intervals along the conveyor, the carriers of each pair being connected respectively to the two conveyor elements, each carrier comprising a mask, lifting means for lifting the blocks in succession to a position to be gripped by a pair of masks, automatic means for actuating the carriers and causing the masks to grip a block while in its lifted position and thereby causing the block to be advanced with the carriers, a spray gun mounted over the path of said blocks, and control means actuated by each block as the latter is lifted by said lifting means to effect the opening of the gun and hold it open during the passage of the block therebeneath, and permitting the gun to remain closed during the passage of an empty pair of said carriers.
